(57) **CLAIM**

The ornamental design for a truck tailgate, as shown and described.

DESCRIPTION

FIG. 1 is a top perspective view of a truck tailgate here

showing the truck tailgate mounted to a truck body indicated in broken lines and not forming part of the design;

FIG. 2 is another perspective view thereof;

FIG. 3 is a side elevation view thereof, the opposing side being a mirror image of the illustrated side;

FIG. 4 is an end elevation view thereof;

FIG. 5 is a top plan view thereof;

FIG. 6 is a bottom plan view thereof;

FIG. 7 is a perspective view of a second embodiment a truck tailgate with the only difference being the configuration of the connection of the side arms of the tailgate to the center rear portion of the tailgate;

FIG. 8 is a side elevation view of FIG. 7, the opposing side being a mirror image of the illustrated side;

FIG. 9 is an end elevation view of FIG. 7;

FIG. 10 is a top plan view of FIG. 7;

FIG. 11 is a bottom plan view of FIG. 7;

FIG. 12 is a perspective view of a third embodiment a truck tailgate with the only difference being the configuration of the connection of the side arms of the tailgate to the center rear portion of the tailgate;

FIG. 13 is a side elevation view of FIG. 12, the opposing side being a mirror image of the illustrated side;

FIG. 14 is an end elevation view of FIG. 12;

FIG. 15 is a top plan view of FIG. 12;

FIG. 16 is a bottom plan view of FIG. 12;

FIG. 17 is a perspective view of a fourth embodiment a truck tailgate with the only difference being the configuration of the connection of the side arms of the tailgate to the center rear portion of the tailgate;

FIG. 18 is a side elevation view of FIG. 17, the opposing side being a mirror image of the illustrated side;

FIG. 19 is an end elevation view of FIG. 17;

FIG. 20 is a top plan view of FIG. 17; and,

FIG. 21 is a bottom plan view of FIG. 17.

The truck tailgate is shown mounted to a truck body (indicated in broken lines in FIG. 1) that is shown for illustrative purposes only and that does not form any part of the claimed design.
